UNITED STATES PATENT OFFICE.

PHILIPP BOCH, OF NEW YORK, N. Y.

BRUSH FOR BOTTLE-WASHING MACHINES.

No. 856,191.

Specification of Letters Patent.

Patented June 4, 1907.

Application filed March 28, 1906. Serial No. 308,507.

To all whom it may concern:

Be it known that I, PHILIPP BOCH, a citizen of the United States, residing in New York, in the borough of Queens and State of New York, have invented certain new and useful Improvements in Brushes for Bottle-Washing Machines, of which the following is a specification.

This invention relates to bottle-cleaning brushes such as used in bottle-washing machines, and the primary object of the invention is to provide a brush for this purpose which readily adapts itself to the interior of the bottle, whereby an efficient cleaning of such bottle may be effected.

The invention also aims to provide a device of this character embodying improved means for mounting the wipers forming the brush, and improved means for normally maintaining the same in contact with the interior surface of the bottle.

The invention consists in the novel features and combinations of parts to be herein-after described and claimed.

In the accompanying drawing, in which the same reference characters denote the same parts throughout the several views, Figure 1 is a longitudinal section through a bottle-cleaning device constructed in accordance with the invention, said device being shown in position to be introduced into a bottle, Fig. 2 is a similar section showing the brush within the bottle, Fig. 3 is an enlarged section on line 3, 3, Fig. 2, Fig. 4 is an end-section of the brush, Fig. 5 is a side-elevation, partly in section, of the brush and its adjunctive parts, Fig. 5^a is a section on line 5, 5, Fig. 5, Fig. 6 is a detail perspective view of a modified construction of brush, Fig. 7 is a further modified form of the brush, and Fig. 7^a is a section on line 7, 7, Fig. 7.

In the drawings, *b* denotes a housing or sleeve which is provided at one end with an elastic head *m* and interior bushing *m*¹ and screwed at the end opposite the head *m* to a tube *b*¹. Disposed within and movable longitudinally with respect to the tube *b*¹ and housing *b* is a spindle *a*, to which rotary motion may be imparted in any suitable manner. The spindle *a* has screwed thereto by means of a screw-plug *a*¹, as best shown in Fig. 5, a tubular end-section *d*. Said tubular section is provided at its free end with a guide-plate *e* which extends into the open end of said tubular section and is disposed

diametrically thereto, as shown in Fig. 4, being secured within said section by means of small screws *e*³ passing through said section at either side into said plate. Said plate *e* is provided at its forward end with shoulders *e*² which abut against the edges of the tubular section, and with a forwardly-extending lug *e*⁴, the function of which will be hereinafter pointed out.

The plate *e* serves as a guide for a brush-actuating shank *g*, which is made of U-shape and straddles said guide-plate, as shown in Figs. 3 and 6, the free ends of said shank being disposed toward the outer end of the tubular section *d*, while the parallel legs of said U-shaped shank fit closely and slide against the guide-plate *e* at either face of the same. A helical spring *d*¹ arranged within the tubular section *d* and abutting at one end against the shank *g*, serves to normally hold said shank in the position shown in Fig. 5, in which said shank protrudes slightly from the open end or mouth of the brush-supporting section *d*. The free ends of the shank *g* are provided with oppositely-inclined transverse edges *g*¹ which impinge against inclined cam-edges *f*^x formed at the inner ends of wiper-holding arms *f* which are pivoted to the lug *e*⁴ of the guide-plate *e* at either side of the same, as shown in Fig. 4. The arms *f* have applied to the same, by means of small screws *f*¹, wiper-holders *f*² which embrace said arms, as shown in Fig. 5^a, and clamp at their meeting edges the wipers *f*³, which are formed of elastic material and extend beyond the holders *f*² at the ends and at the front edges of the same, as shown in Fig. 5. The spring *d*¹ in normally holding the actuating-shank *g* in its forward position, causes the wipers *f*³ to project oppositely at right angles to the spindle *a*, by the action of the co-operating edges *g*¹, *f*^x constituting cam-positions of said shank and the respective wiper-arms.

In the modification shown in Fig. 6 the wipers, instead of being applied to the wiper-arms by means of removable holders, are permanently secured directly to the wiper-arms *f*⁵, which for this purpose are bifurcated, as shown, and have the wipers retained within such bifurcations by means of rivets *r*.

Fig. 7 shows a brush which is used to clean bottles having deep convex bottoms. In this form the cam-edges of the actuating-shank *g*^x extend at right angles to the latter.

and the coöperating edges of the wiper-arms are so formed that when the shank is in its normal position it will hold the wipers f^e at an obtuse angle to each other, and thereby conform at their forward edges to the bottom of the bottle, as indicated in dotted lines in Fig. 7. In order that the ends of the wipers may properly contact with the side-wall of the bottle, such ends are inclined with respect to the body-portion of said wipers. In this form, the wiper-arms f^e , instead of being bifurcated at their ends, are formed of sheet-metal which is doubled upon itself and is clamped upon the wipers by means of rivets, as shown in Fig. 7^a.

The operation of the improved bottle-cleaning device is as follows: When the device is in its normal position the parts are in the position shown in Fig. 1, in which the wipers of the brush are held parallel to each other by means of the bushing m^1 within which said wipers are disposed. The bottle to be cleaned has its mouth placed against the head m of the housing and said housing is then pushed backwardly on the spindle a by forcing said bottle in the direction of the brush. By reason of the movement of the bottle in this direction, the wipers, which are held parallel to each other, pass through the mouth of the bottle to the interior of the same, and as soon as said wipers are disengaged from the wall of the bushing, the head m , and the neck of the bottle, they spread, as indicated by dotted lines in Fig. 2, and assume the position shown in full lines in said figure, in which they extend at approximately right angles to the actuating-spindle at opposite sides of the same and contact at their outer ends with the inner surface of the bottle-wall. This movement of the wipers into expanded position is effected by the helical spring d^1 which normally holds the actuating-shank g in extended position, in which position its inclined ends act upon the inclined cam-edges of the wiper-arms in such a manner as to force said arms into the position just indicated. When the wipers of the brush have assumed the position shown in Fig. 2, rotary motion is imparted in any suitable manner to the spindle a , and consequently to the brush. During the rotation of the brush the ends of the wipers constituting the same rotate in contact with the side-wall of the bottle and thereby thoroughly clean the same and as the bottle is reciprocated over said brush the interior of the former is thoroughly cleansed throughout its length, the forward edges of the wipers conforming to and cleaning the bottom of the bottle when such bottom is forced against the rotating brush during the manual reciprocation of the bottle. The brush may be made to rotate at comparatively great speed so that the thorough cleansing of the bottle is effected in a very short time, after which the bottle is with-

drawn over the brush and the latter again confined within the housing. The device is then ready for use upon another bottle.

Having thus described my invention, I claim as new and desire to secure by Letters Patent:

1. In a bottle-cleaning device, in combination, a spindle, a tubular end-section carried thereby, a plate disposed within said end-section and extending longitudinally thereof, wipers pivoted to said plate, and a wiper-actuating device.

2. In a bottle-cleaning device, in combination, a tubular section, a plate disposed diametrically and longitudinally of said section and extending beyond the same at one end, wipers pivoted to the outwardly-extending portion of said plate, and a wiper-actuating device.

3. In a bottle-cleaning device, in combination, a tubular section, a plate within the same and extending longitudinally thereof, wipers pivoted to said plate at opposite faces of the same, and a wiper-actuating device.

4. In a bottle-cleaning device, a tubular section, a plate extending longitudinally thereof and disposed within the same, pivoted wipers, and a wiper-actuating device guided on said plate.

5. In a bottle-cleaning device, the combination of a tubular member, a guide-plate disposed within said member, pivoted wipers, and a wiper-actuating shank guided longitudinally on said guide-plate.

6. In a bottle-cleaning device, in combination, a spindle, a tubular end-section carried thereby, a plate within and extending longitudinally of said section, wipers pivoted to said plate, and a wiper-actuating device guided on said plate.

7. In a bottle-cleaning device, a spindle, a tubular end-section carried thereby, a plate within and extending longitudinally of said member, wipers pivoted to said plate at one end, and a wiper-actuating device guided longitudinally of said section on said plate.

8. In a bottle-cleaning device, in combination, a spindle, a hollow end-section carried thereby, a plate within and extending longitudinally to said section, wipers pivoted to said plate at one end of the same, said wipers being located at opposite faces of said plate, and a wiper-actuating shank guided longitudinally of said plate and engaging both of said wipers.

9. In a bottle-cleaning device, a tubular member d , a plate e within and extending longitudinally of said member, wipers, and a wiper-actuating shank g straddling said plate and guided therealong.

10. In a bottle-cleaning device, a tubular member, a guide-plate disposed within and extending longitudinally of said member, wipers pivoted to said plate, and a wiper-

actuating shank straddling said plate and guided therealong.

11. In a bottle-cleaning device, in combination, a tubular section, a plate disposed within said section and extending diametrically thereof, pivoted wipers, and a wiper-actuating shank embodying parallel legs guided longitudinally on opposite faces of said plate.
12. In a bottle-cleaning device, a guide-plate, wipers pivoted thereto at either face of the same, and a wiper-actuating shank embodying parallel legs straddling said guide-plate and engaging at their ends with said wipers.

13. In a bottle-cleaning device, in combination, a tubular member, a guide-plate extending longitudinally and diametrically of said member, pivoted wipers, and a U-shaped wiper-actuating shank guided on said guide-plate.

14. In a bottle-cleaning device, the combination, with a spindle, of a tubular end-sec-

tion carried thereby, a guide-plate within said section, pivoted wipers, and a U-shaped wiper-actuating shank straddling said guide-plate and guided longitudinally along the same.

15. In a bottle-cleaning device, the combination, with a spindle, of a tubular end-section carried thereby, a guide-plate extending longitudinally and diametrically of said section, wipers pivoted to said guide-plate at one end and at either face of the same, and a wiper-actuating shank embodying legs which straddle said guide-plate and are guided longitudinally therealong, said legs engaging at their ends with said wipers.

In testimony, that I claim the foregoing as my invention, I have signed my name in presence of two subscribing witnesses.

PHILIPP BOCH.
